CLAIM

The ornamental design for an electronic information terminal, as shown and described.

DESCRIPTION

FIG. 1 is a front, right side perspective view of an electronic information terminal showing our new design;

FIG. 2 is a front elevation view thereof;

FIG. 3 is a top plan view thereof;

FIG. 4 is a left side elevation view thereof; and,

FIG. 5 is a right side elevation view thereof.

In the drawings, the broken lines shown in FIGS. 1, 2, and 5 indicate portions of the article not claimed and form no part of the claimed design.

1 Claim, 4 Drawing Sheets

FIG. 1

FIG. 2

FIG. 3

FIG. 4

FIG. 5
